CLAIM

The ornamental design for a control device, as shown and described.

DESCRIPTION

(63) Continuation of application No. 29/740,579, filed on Jul. 6, 2020, now Pat. No. Des. 958,761.

FIG. 1 is a front perspective view of a control device showing our new design;

(51) LOC (14) Cl. 13-03

FIG. 2 is a front view thereof;

(52) U.S. Cl.

FIG. 3 is a left side view thereof;

USPC D13/169

FIG. 4 is a right side view thereof;

(58) Field of Classification Search

FIG. 5 is a top view thereof;

USPC D13/162, 164, 171, 169, 174

FIG. 6 is a bottom view thereof;

CPC .. H01H 3/12; H01H 9/02; H01H 9/16; H01H

FIG. 7 is a front perspective view of a second embodiment thereof;

9/18; H01H 9/181; H01H 9/182; H01H

FIG. 8 is a front view thereof;

13/04; H01H 13/06; H01H 13/14; H01H

FIG. 9 is a left side view thereof;

(Continued)

FIG. 10 is a right side view thereof;
 FIG. 11 is a top view thereof; and,
 FIG. 12 is a bottom view thereof.
 The dashed broken lines illustrate structure or features
 which form no part of the claimed design.

1 Claim, 8 Drawing Sheets

(58) Field of Classification Search

CPC .. 39/085; H05B 39/086; H05B 39/088; H03K
 17/96; H03K 17/962

See application file for complete search history.
